UNITED STATES PATENT OFFICE.

HARRY SUMNER JACKMAN, OF ST. PAUL, MINNESOTA.

TIGHTENER FOR VIOLIN E STRINGS.

Application filed June 11, 1921. Serial No. 476,707.

To all whom it may concern:

Be it known that I, HARRY SUMNER JACKMAN, a citizen of the United States, and a resident of St. Paul, in the county of 5 Ramsey and State of Minnesota, have invented a new and Improved Tightener for Violin E Strings, of which the following is a description.

My invention is more particularly intended for embodiment in a tightener for the metal "E" string in musical instruments.

The general object of the invention is to provide a tightener of the indicated character improved in various particulars whereby 15 it will possess distinctive characteristics and advantages among which are that, a direct pull is exerted on the string by the tightening device; the tightening of the string is effected in a manner to avoid any tendency 20 of the tightener to throw the tail-piece of the instrument out of position; the tightener presents no members at the under side of the tail-piece of a character that would be liable to scratch or injure the belly of the instrument; and the important result is obtained 25 that the mass of metal usual in tighteners of the indicated type is materially reduced and thereby the detrimental effect of the tightener on the vibrations set up in the instrument when being played is greatly decreased.

The above and other advantages will appear by the novel construction hereinafter described.

35 Reference is to be had to the accompanying drawing forming a part of this specification, it being understood that the drawings are merely illustrative of one example of the invention.

40 Figure 1 is a plan view of a tightener embodying my invention showing the same in use in connection with a tail-piece and string shown in part;

Figure 2 is a longitudinal vertical section;

Figure 3 is a section on the line 3—3, Figure 2;

Figure 4 is a section on the line 4—4, Figure 2;

50 In the drawings the letter A indicates an ordinary tail-piece; α the key hole slots therein, and B a portion of an "E" string.

In carrying out my invention in accordance with the illustrated example a base plate 10 55 is provided of a size to overlie the tail-piece A at the hole α and has a tubular depending

stud 11 adapted to extend through the enlarged end of the hole α , said stud being externally threaded to receive a nut 12 to bear against the under side of the tail-piece 60 A and clamp the latter between said nut and base plate. The stud 11 is internally threaded also to receive an adjusting screw 13 having a milled head or the like for turning it.

65 A lever 14 is provided slightly arched for its major portion and formed with a longitudinal slot 15 through which the screw 13 extends so that the head of the screw bears on top of said lever. At the forward end 70 the lever 14 has a hook 16 about which the string B is bent and at the same end beneath the hook 16, said lever 14 is formed with a depending cam 17 adapted to extend through a slot 18 in a lateral extension 10^a 75 of the base plate 10. Said cam presents an oblique cam surface 17^a at the under side adapted to bear against the forward wall of the slot 18 and the lower end of the cam terminates in a toe 19 projecting through 80 the slot 18 to the under side of the base plate 10.

85 With the above described construction the lever 10 rests on top of the base plate between the same and the head 13 and upon pressure being applied to the lever by the turning of the screw the cam surface 17^a in its engagement with the base 10 at the end of the slot 18 forces the lever longitudinally in its own plane thereby exerting a pull on 90 the string B. If the screw be turned backward clear of the lever 14 or in fact if the screw be completely removed, the lever 14 will nevertheless retain its position in association with the base plate 10 as the weight 95 of the lever will cause the cam 17 to drop through the slot 18 and position the toe 19 beneath the base plate directly adjacent to the tubular stud 11, thereby retaining the lever against complete displacement. A 100 curved form is given to the lever 14 because the lever at one end moves more or less in a curved path, the center of which changes with the movement of the lever longitudinally in response to the engagement of the 105 cam 17 with the base.

I would state in conclusion that while the illustrated example constitutes a practical embodiment of my invention, I do not limit myself strictly to the mechanical details herein illustrated, since manifestly the same can be considerably varied without de-

parture from the spirit of the invention as defined in the appended claims.

Having thus described my invention, I claim:

- 5 1. A tightener for musical strings comprising a base having a bore and an opening, an element having a curved under face to engage the wall of said opening positioned on said base, a screw holding said element and 10 said base in position, a hook member at one end of said element for connecting thereto a string to be tightened, said element when subjected to pressure by said screw moving in a plane transverse to the axis of said bore.
- 15 2. A device of the class described including a base, means to secure the base in position, an element having means for connection with the string to be tightened and presenting a cam surface at the under side 20 contacting with the base, and means to exert pressure on said element, said element being free to slide and to shift longitudinally under said pressure for exerting a pull on the string.
- 25 3. A tightener for a string of musical instruments including a base having a depending tubular stud adapted to pass through a tail-piece and provided with a nut to bear against the tail-piece, said base 30 presenting a slot, a string-receiving element having a member extending into said slot and presenting a cam surface contacting with a wall of the slot, and a screw having

threaded engagement with said stud and adapted to exert pressure on said element. 35

4. A tightener for a string of musical instruments including a base, means to clamp said base in position, said base having a slot, a string receiving element having a cam extending into said slot and engaging said base, said cam terminating in a toe adapted to pass through the base to the under side, and means to exert pressure on said element to force the cam thereof against the base for shifting said element longitudinally. 40 45

5. A tightener for a string on a musical instrument including a base plate formed with a slot, a string-engaging element having a cam member extending into said slot 50 and contracting with the base, said element having a longitudinal slot, and a screw extending through the slot of said element and engaging said base.

6. A tightener for a musical instrument 55 string, including a base presenting an opening, a lever of curved form resting on the base and engaging the wall of said opening, said lever having means to engage a string, means for pressing said lever against 60 said base, said lever when pressed being slid able on the base in a path transverse to said pressure means, thereby exerting a pull on the string.

HARRY SUMNER JACKMAN.
